Atty.

UNITED STATES PATENT OFFICE.

MARCEL ADOLPHE HARDY, OF HENNEBONT, FRANCE.

MANUFACTURE OF EXTRUDED METAL SECTIONS.

Application filed June 14, 1921. Serial No. 477,451.

To all whom it may concern:

Be it known that I, MARCEL ADOLPHE HARDY, a citizen of the Republic of France, residing at Hennebont, Department of Morbihan, France, Chemin du Meunier, have invented a new and useful Improvement in the Manufacture of Extruded Metal Sections, of which the following is a specification.

This invention relates to the manufacture of metal sections by the method known as extrusion, which consists in compressing by means of a piston moving in a cylinder, the closed end of which is provided with an opening having the desired cross-sectional profile, a block or mass of metal upon the frontal surface of which the piston presses.

This method which affords good results with metals or alloys which are malleable in the cold or at relatively low temperatures, has not hitherto been applicable in a practical manner for steel.

The material to be worked must in fact be heated in most cases, and to avoid too rapid cooling of the mass of metal it is necessary to employ a cylinder with heat-resisting walls or to raise the walls of the cylinder to a certain temperature.

When it is a question of working metals malleable at low temperatures, like copper, brass or the like it is possible to construct these walls in a sufficiently strong and heat-resisting manner to withstand the pressure without distortion and to avoid as far as possible any cooling of the mass. But the same does not apply for steel, which has to be raised to a very high temperature in order to be workable, for when the cylinder walls are not at a sufficient temperature the steel cools rapidly along the walls, and the force necessary to compress the metallic mass becomes too great. On the other hand, the temperature to which these walls can be raised is limited by the resistance to deformation which they are required to offer.

The present invention has for object to allow the application of this method of manufacture to steel and other metals, alloys or materials of any kind which require to be worked at high temperature.

The invention consists in arranging the compressing piston in such a way as to compress the metal, not over its entire frontal surface as in the known method, but only over the central portion of this surface, so as to reserve between the piston and the in-

ner wall of the cylinder a mass of metal which acts the part of a heat-resisting and insulating layer for the central part of the block, the latter part thus retaining sufficient plasticity to be able to be worked as required. 60

There can in this way be utilized a cylinder of which the walls are heated to a temperature which does not affect its qualities of resistance, or even in certain cases a cylinder of which the walls are heated only 65 to a very small extent or not at all.

In order better to explain the subject of the invention, Figure 1 of the accompanying drawing shows diagrammatically the section of the arrangement employed in the known 70 method, while Figure 2 shows the diagrammatic section of the arrangement in accordance with the present invention.

In Figure 1, *a* is the cylinder and *b* the piston which compresses the block of metal 75 *c*, bearing over the whole frontal surface *m n*. In the arrangement of Figure 2, on the contrary, the piston *d* acts only upon the central part *p q* of the block of metal *c*, which has remained plastic, whereas all the peripheral 80 part has formed in cooling a kind of insulating layer.

Suitable arrangement must evidently be provided for opening the cylinder in order to allow of introducing therein the block of 85 metal to be worked, and of withdrawing therefrom the unused mass of metal when the piston has completed its stroke.

The method may be applied both to blocks of metal heated up to their working 90 temperature, and to metal blocks still in the pasty condition, when incompletely solidified after having been cast.

It may also be applied, whether the block is composed of a single homogeneous substance or of several parts placed one within the other, of the same or of different materials, heated altogether or separately at the same or at different temperatures. 95

It may be applied equally as well to any 100 metal or alloy whatever as to steel, or again to any metallic or other substance requiring to be worked at any temperature higher than the ordinary temperature.

Claims—

1. A method of manufacturing extruded metal sections, comprising exerting pressure on a mass of metal to be worked, said pressure being applied on an area whose diameter is substantially less than that of a container 110

in which the metal is placed; whereby a heat insulating layer of said metal is formed between the interior surface of the container and a means for exerting said pressure.

- 5 2. A metal extruding device, comprising a closed container, a mass of workable metal, positioned in said container, a compressing member operable in the container positioned

so as to exert its main pressure on a central portion only of the mass of metal.

In testimony whereof I have signed my name to this specification.

MARCEL ADOLPHE HARDY.
